POSTURE PROTECTING BRASSIÈRE

John R. Fratianni, Brooklyn, N. Y.

Application January 25, 1947, Serial No. 724,441

1 Claim. (Cl. 2—32)

1 This invention relates to an improved brassière and one of its objects is to provide a brassière with means for bracing the back of the wearer, so that the tendency to collapse the back and congest the bust will be corrected, and a more healthful posture will be maintained by the wearer, without suffering any discomfor-

ture. Another object of the invention is the provision of a brassière of this general construction with elastic sections secured to the back wall of the garment, so that bending and walking movements will have the necessary freedom, while the posture protecting action of the bracing means will be maintained.

With the above and other objects in view the invention comprises certain new and useful constructions, combinations and arrangements of parts, clearly described in the following specification, and fully illustrated in the drawings, in which:

Fig. 1 is a front perspective view, showing the garment applied to a wearer, indicated in dotted lines.

Fig. 2 is a rear perspective view thereof.

Referring to the drawings which show the design of a finished product, 5 designates the rear wall of the brassière, which is formed with shoulder strap extensions 6 and 7. The extension 6 is formed on a panel or section 8, which is provided with a tubular strap or strip 11, having a stiffening brace of steel or whalebone enclosed thereby, and which is disposed in line with the normal tensional pull developed on the shoulder strap extension 6. The shoulder strap extension 7 is carried by a panel which is provided with a tubular strap or strip 12, in which a stiffening brace of steel or whalebone is inserted. This brace is disposed in line with the normal tensional pull developed upon the strap extension 7.

These two panels are connected to each other by means of an intermediate strip 13 of elastic fabric, which is united at its side edges by the seams 14 and 15 to said panels. An elastic supporting device 16 is connected to the lower end of the tubular strap 11, and this has the usual connection with an under garment of the user, so that tension will be maintained upon both ends of the brace. The tubular strap 12 is similarly connected to an elastic supporter 17.

To the panel 8 which carries the stiffening brace and enclosing tubular strap 11 the panel 19 is connected by the seam 20. This panel includes the lower elastic fabric section 21 and

the upper non-elastic section 22, which is united thereto by means of the V-shaped stitching 23. This panel 19 carries an edge strip 24 which is provided with a series of hook eyes 25.

5 To the panel 26, which carries the tubular strap 12, the bust enclosing front wing or wall 27 is connected by means of the side panel 28. This side panel includes the lower elastic 29 and the upper non-elastic section 30, which are united to each other by means of the V-shaped stitching 31. The front wing is composed of tailored sections, which include the bottom or lower horizontal section 32, having maximum resistance to stretching, and which may be a double

10 layer fabric, the single layer intermediate fabric section 33, and the upper cross strip 34 of lace edging, having a self fitting or covering action.

The front bust covering wing is provided with shoulder strap extensions 35 and 36, which are 15 connected to the shoulder strap extensions 6 and 7 by means of the elastic straps 38 and 39. The free edge of the front wing is provided with a strip 40, which carries a series of hook and eye hooks 41, designed to have coupling engagement 20 with the eyes 25. The front wing is also provided with elastic strap supporters 42 and 43, which are disposed in line with the shoulder straps.

25 Because of this arrangement and construction 30 the stiffening braces, which extend high up against the back of the user, are held in close supporting engagement with the user's back, so that the torso of the user is braced against such deformation which results in a bulging back and a collapsed or congested bust.

The effect in actual service use is to elevate 35 the bust and straighten the back, so that a natural and comfortable posture is maintained, and fatigue is reduced, with the result that the wearer 40 appears more attractive.

It is understood that various changes in the 45 details of construction, their combination and arrangement, may be made in carrying out the invention, defined by the claim herein set forth.

Having described the invention, I claim:

A brassière having a back wall and a front wall 50 tailored to support and fit the bust of the wearer, said back wall comprising alternate elastic and fabric sections, the fabric sections extending vertically and spaced by an elastic section and each fabric section having an elastic section outwardly of the same, stiffening braces and means for securing the same to the respective fabric back wall sections and elastic shoulder straps connecting 55 said fabric back wall sections to the front wall

and disposed in line with the stiffening braces so that the tensional pulls will be directly applied to said braces and whereby the braces may be adjusted on the back of the wearer to the right or left depending upon the position of the shoulder straps and the direction of pull of the same.

JOHN R. FRATIANNI.
